Primary Examiner—A. Hugo Word**Assistant Examiner—Doris Clark****Attorney, Agent, or Firm—Oblon, Spivak, McClelland, Maier & Neustadt****[57]****CLAIM**

The ornamental design for a metal door with grille, as shown and described.

DESCRIPTION

FIG. 1 is a front elevational view of a metal door with grille showing a front elevational view of a first form of my new design, the rear elevational view being a mirror image of FIG. 1;

FIG. 2 is a side elevational view thereof, the opposite side being a mirror image of FIG. 2; and,

FIG. 3 is a front elevational view of a second embodiment thereof, the rear elevational view being a mirror image of FIG. 3, and the side edge views identical to FIG. 2 hereof.

FIG. 1

FIG. 2

FIG. 3
